UNITED STATES PATENT OFFICE.

JOSEPH F. TAUBER, OF LIDGERWOOD, NORTH DAKOTA.

MAIL-BOX.

1,286,144.

Specification of Letters Patent.

Patented Nov. 26, 1918.

Application filed May 9, 1918. Serial No. 233,510.

To all whom it may concern:

Be it known that I, JOSEPH F. TAUBER, a citizen of the United States, residing at Lidgerwood, in the county of Richland and 5 State of North Dakota, have invented certain new and useful Improvements in Mail-Boxes, of which the following is a specification.

This invention relates to mail boxes and 10 more particularly to rural delivery mail boxes, the primary object being to provide an apparatus whereby the mail box may be transported from the roadside to the door of the person to whom the mail is to be delivered.

One of the principal objects of the invention is to provide a traveling mail box supported on a run-way formed by supporting wires stretched from the dwelling to a convenient point at the roadside and associated 20 with actuating means by which the owner can cause the mail box to be transported from the door way to the roadside for receiving the mail from the carrier after which 25 the actuating means may be operated for returning the box to a point within convenient reach of the owner of the dwelling thereby making it unnecessary to leave the doorway.

30 A further object of the invention is to provide a device of this character which consists of comparatively few parts and is simple in construction but durable and well adapted to withstand the rough usage to 35 which devices of this character are ordinarily subjected.

For a full description of the invention and the advantages and merits thereof, reference is to be had to the following description and accompanying drawings, in 40 which:—

Figure 1 is a perspective view of the invention mounted in position for use.

Fig. 2 is a transverse section taken 45 through a portion of the device as indicated by the line 2—2— of Fig. 1.

Fig. 3 is an enlarged elevation of a portion of the device, and

Fig. 4 is a section taken on the line 4—4 50 of Fig. 1.

Referring to the drawings, wherein like numerals of reference indicate corresponding parts throughout the several views, the upright standard 1 may indicate either a 55 post at the side of the dwelling or the side of a doorway in the dwelling. The post 2

may be mounted at the roadside or at any point at some distance from the dwelling but preferably at whatever point the rural mail carrier finds it most convenient to stop 60 to deliver the mail.

Intervening posts 3 are mounted between the dwelling and the end post 2 and the usual telegraph poles or telephone wire supporting poles may be utilized for this purpose if convenient.

A pair of supporting wires 4 are attached to the posts 1 and 2 and are laterally spaced apart to form a runway or trackway for supporting the mail box during its travel from 70 one post to the other. The posts 1 and 2 are each provided with a laterally projecting arm 5 to which the ends of the wires 4 are fastened, so that the wires are held in properly spaced relation. To support the intervening portions of the wires 4 each post 3 is provided with a bracket which consists of the upstanding arms 6 having their ends bent toward each other to provide the angularly disposed ends 7 the terminals of which 75 are provided with sleeves 8 through which the wires 4 are extended. The sleeves should be of relatively thin metal so that not much of an obstruction will occur at the points where the brackets are attached to the wires. 80 The horizontal bar 9 connects the portion 6 of each bracket and from this bar the lugs 10 depend for supporting a roller 11. A second stronger roller 12 has its ends journaled in the upright arms 6 and these rollers are 85 for the purpose of supporting the draw cable and preventing frictional contact with portions of the bracket when the cable is in operation.

In this manner, the wires which form the 90 runway, are properly supported to extend for any desired distance and the mail box 13 is adapted to travel on the runway from one end to the other thereof. The mail box is preferably constructed of metal and may 100 be of any desired shape. Each side of the mail box, has depending therefrom, a flange 14 and these flanges are disposed at the same angle as the angle of the portions 7 of the bracket. Supporting wheels 15 are attached to the flanges 14 near the ends of the latter so that four wheels are provided for the mail box, and since these are disposed beneath the flanges, it will be readily apparent that snow and hail will not gain access to 105 the wheels and consequently cannot hinder operation of the device during bad weather.

Pivot pins 16 are employed to hold the wheels connected to the flanges and each wheel is provided with a deep annular groove, the groove preferably being three or 5 four inches deep to prevent accidental displacement of the mail box from the runway. Furthermore, the weight of the mail box above the runway causes the wheels to press against the wires 4 and have a tendency to 10 force the wires away from each other so that casual displacement by the wind or otherwise is prevented. The draw cable 17 has one end fixed to the front end of the box as indicated at 18 and the opposite end 15 fixed to the rear end of the box as indicated at 19. This draw cable passes over a pulley 20 mounted on the end post 2 and also over a drive pulley or wheel 21 mounted on the post 1. This wheel 21 is supported by a 20 bracket 22 which is attached to the post 1 and supports the shaft to which the crank 23 is connected. This shaft may be driven by a small engine or motor where this source of power is available. A pulley 24 is provided for this purpose. Actuation of the 25 crank, however, will cause the cable 6 to operate for either drawing the mail box toward the house, or causing it to travel on the runway toward the roadside to the post 30 2. The wires 4 which form the runway will always remain taut since they are rigidly secured to the end post. The intervening brackets will properly support the wires to 35 prevent sagging of the runway at any point in the length thereof. Wear on the cable however, is prevented by the rollers 12 and 11 and since these cables will have a tend-

ency to sag it will be readily apparent that they will be properly supported by the rollers and frictional contact which would 40 otherwise cause considerable wear, will be materially prevented by engagement with the rollers.

The foregoing description and accompanying drawings have reference to what 45 might be considered to be the preferred or approved form of my invention. I desire it to be understood that I may make such changes in construction and arrangement of parts, material, dimensions and et cetera, as 50 may prove expedient and fall within the scope of the appended claim.

Having thus fully described my invention, what I claim as new and desire to secure by Letters Patent, is:—

A device of the character described comprising supports, brackets fixed to the supports and including laterally spaced arms having their terminals provided with sleeves, a runway including laterally spaced 60 wires extending through the sleeves, the ends of the wires being fixed to the end posts and drawn taut, a mail box having side flanges disposed at an angle with respect to the sides of the box, wheels attached 65 to the flanges and engageable with the wires, and means attached to the mail box for drawing the latter over the said wires.

In testimony whereof I affix my signature in presence of two witnesses.

JOSEPH F. TÄUBER
